UNITED STATES PATENT OFFICE.

HENRY L. PLUMMER, JR., AND CHARLES D. WITHERSPOON, OF PETERSBURG, VIRGINIA.

MACHINE FOR CREEASING LEATHER.

SPECIFICATION forming part of Letters Patent No. 746,150, dated December 8, 1903.

Application filed March 18, 1903. Serial No. 147,656. (No model.)

To all whom it may concern:

Be it known that we, HENRY L. PLUMMER, Jr., and CHARLES D. WITHERSPOON, citizens of the United States, residing at Petersburg, 5 in the county of Dinwiddie and State of Virginia, have invented certain new and useful Improvements in Machines for Creasing Leather, of which the following is a specification.

10 This machine is designed to score and burn a crease in the surface of leather, such as leather straps and bindings.

The machine comprises means for supporting and feeding forward the leather strap and 15 a revolving creaser which is run at high speed, so that it not only forms the indentation, but heats the leather along the depressed line by friction to a temperature which discolors the leather, producing a brown or black crease.

20 The invention will be more readily understood by reference to the accompanying drawings, in which—

Figure 1 is a transverse vertical section of the upper part of the machine, taken on line 25 I I of Fig. 2. Fig. 2 is a vertical longitudinal section taken on line II II of Fig. 1, and Fig. 3 is a side elevation of the machine.

The machine comprises a frame 1, of wood or metal, supporting a feed-table 2. Upon 30 this table are secured a number of parallel guide-strips 3, arranged in pairs. Beneath the table is a transverse horizontal feed-roll 4, carried by a shaft 5, which is journaled in boxes 6. Each of these boxes is vertically 35 movable in a hanger 7, secured to the under face of the table, and is supported upon a rubber block 8, carried by a steel plate 9, which rests on the upper end of a set-screw 10, passing through a threaded opening in the base of 40 the hanger. The feed-table has a transverse opening 11 directly above the feed-roll, and the roll projects into this opening and slightly above the upper surface of the table, so as to press against and feed forward a strap which 45 is pushed over it between the guides 3. One end of the shaft 5 carries a sprocket-wheel 12, which is connected by a driving-chain 13 to a sprocket-wheel 14 on a shaft which carries a driving-pulley 15.

Directly above and parallel to the feed-roll 50 is a shaft 16, which carries the creaser or creasers. The shaft is journaled in boxes 17 and has a driving-pulley 18. Each of the creasers (shown as five in number) is a disk 19, having a pair of peripheral ribs 20, one 55 near each edge of the disk. Between each pair of creasing-disks is a spacing-collar 21. The disks and collars are bored to fit smoothly upon the shaft and are clamped against a shoulder 22 at one end of the shaft by a nut 60 23, running on a thread 24, near the other end of the shaft.

In using the machine the leather strap is fed forward between the guides 3 and entered between the feed-roll and one of the 65 creasing-disks. The slowly-revolving roll, bearing against the under surface of the strap, thus feeds it forward and out the other end of the machine. Meanwhile the ribs on the creasing-disk, which is run at a high speed, 70 not only indent the leather as soon as they come in contact with it, but by reason of the great friction occasioned by the fact that they slip upon the leather as it is moved slowly beneath them by the feed-roll discolor the depressed line and may be said to burn it to a 75 deep brown or black. It will be evident that the speed of the feed-roll rather than that of the creasing-disk determines the rate of feed of the strap, since it bears against the 80 strap entirely across its lower surface, while only the narrow ribs 20 of the creasing-disk come in contact with the strap.

It is important to run the creasing disk or disks in the opposite direction to that of the 85 feed-roll relatively to the leather to increase the slip and friction of the creasing-ribs upon the leather. A creased line can thus be burned into the leather at a much lower rate of speed than if the creasing-disk revolves in 90 such direction as to tend to feed the leather forward.

While the machine shown is especially designed to crease a strap, it is obvious that the guides may be omitted and a crease burned 95 in a piece of leather of any width. By using a creaser of narrow diameter the leather may be shifted as it is passed through the machine

to produce a curved or ornamental line. While the feed-roll shown is a convenient means for carrying the leather forward under the creasers, the leather may be fed by hand or by well-known mechanism.

We claim—

1. A machine for creasing leather, comprising means for slowly feeding forward the leather, a revolute creaser, means for driving the creaser at a sufficient speed to score and burn a depressed line in the leather, and guides for retaining the leather beneath the creaser as it is fed forward, as set forth.
2. A machine for creasing leather, comprising a feed-roll, means for driving the roll at a comparatively low speed, a revolute creaser, means for driving the creaser at a sufficient speed to score and burn a depressed line in the leather, and guides for retaining the leather beneath the creaser as it is fed forward, as set forth.
3. A machine for creasing leather, comprising a feed-roll journaled in yielding bearings at each end, means for driving the feed-roll at a comparatively low speed, a revolute creaser, means for driving the creaser at a high speed, and guides for retaining the leather beneath the creaser as it is fed forward, as set forth.
4. A machine for creasing leather, comprising means for slowly feeding forward the leather, a revolute creaser, and means for driving the creaser at a high speed and in the

opposite direction to the feed of the leather, as set forth.

5. A machine for creasing leather, comprising a feed-roll, means for driving the roll at a comparatively low speed, a revolute creaser, and means for driving the creaser at a high speed and in the opposite direction to the feed of the leather, as set forth.

6. A machine for creasing leather, comprising a feed-table carrying guides, a feed-roll projecting through the table, means for driving the feed-roll at a comparatively low speed, a creasing-disk having one or more ribs running between said guides, and means for driving the creasing-disk at a high speed, as set forth.

7. A machine for creasing leather, comprising a feed-table carrying guides, a feed-roll journaled in yielding bearings and projecting through the table, means for driving the feed-roll at a comparatively low speed, a creasing-disk having one or more ribs running between said guides, and means for driving the creasing-disk at a high speed, as set forth.

In testimony whereof we affix our signatures in presence of two witnesses.

HENRY L. PLUMMER, JR.
